UNITED STATES PATENT OFFICE

148,332

DESIGN FOR AN INVERTER

Philip F. Scofield, Cleveland Heights, and Arnold R. Keistman, Shaker Heights, Ohio, assignors, by mesne assignments, to Jack & Heintz Precision Industries, Inc., Cleveland, Ohio, a corporation of Delaware

Application February 8, 1946, Serial No. 126,392

Term of patent 3½ years

(Cl. D26—5)

To all whom it may concern:

Be it known that we, Philip F. Scofield and Arnold R. Keistman, citizens of the United States, residing at Cleveland Heights and Shaker Heights, respectively, in the county of Cuyahoga and State of Ohio, have invented a new, original, and ornamental Design for Inverter, of which the following is a specification, reference being had to the accompanying drawing, forming part thereof, wherein:

Figure 1 is a side perspective view of an inverter showing our new design;

Figure 2 is a view in front elevation; and
Figure 3 is a view in rear elevation.

We claim:
The ornamental design for an inverter, substantially as shown.

PHILIP F. SCOFIELD.
ARNOLD R. KEISTMAN.
